W. NEED & C. J. JENKINS.

Threshing Mach.

Patented May 9, 1835.

8818X

Stapleton C. Need & William B. Carpenter,
of the County of Albemarle and State of Virginia,

Letters Patent.

The Schedule referred to in these Letters Patent, and making part of the same, containing a description in the words of the said Stapleton C. Need and William B. Carpenter, Inventors of their improvement in Archibald Douglas' Spike Threshing Machine.

To all to whom these presents shall come:

Be it known that we Stapleton C. Need and William B. Carpenter of the County of Albemarle and State of Virginia, have invented a new and useful improvement in Archibald Douglas' Spike-wheel Threshing Machine and the following is a full and exact description of the construction and operation of the said machine as invented or improved by us. The spikes used by us are $1\frac{1}{2}$ inches by $\frac{1}{4}$ inch 6 inches long, drove into the cylinder 4 inches projecting. There is a mortise through each spike through which passes a bar of iron $3\frac{1}{4}$ by $3\frac{1}{8}$ that bar let in a groove length ways in the cylinder the top edge ranging with the surface of the cylinder. The bands on each end of the cylinder, confining each end of the bars that pass through each spike, the whole cylinder covered with sheet iron. There is two other places of securing the spikes which we leave in our power, one for the concave, say a double shank drawn on each edge of the spike, they drove through and clinched on the opposite side, the other with a notch forged in the back of the spike, the bar resting in the notch instead of passing through the spikes, our model will explain why point more perfect and all the different shapes of spikes. This machine can be used to thresh down or up as may be desired.
